COMBINATION INFLOW CONTROLLING AND FLUID DISCHARGE MEANS

Marvin S. Young, Scarsdale, and Abraham Novick, Flushing, N. Y., assignors, by direct and mesne assignments, to Socony-Vacuum Corporation, a corporation of New York

Application August 27, 1928. Serial No. 302,342

14 Claims. (Cl. 226—93)

This invention relates to means for transferring liquid from one container to another, the principal purpose of the invention being to provide cooperative instrumentalities, for this purpose, on the two containers, so formed that the receiving container cannot easily be filled except through such instrumentalities.

In Letters Patent of the United States granted to us August 28, 1928, No. 1,682,544, for Combination inflow controlling and fluid discharge means, we have disclosed apparatus for dispensing oil or other liquid commodities in small measured quantities, by means of bottles so constructed as to be refillable conveniently only from a particular source of supply, through connecting means provided for the purpose. The present invention relates particularly to connecting means used in, or suitable for use in that connection or for any analogous purpose, and the present application is, in part, a continuation of the application on which our said patent was granted.

In the accompanying drawings:—

Fig. 1 is a diagrammatic side view of a dispensing pump and receptacle with our invention incorporated therein.

Fig. 2 is a plan view of the receptacle with the improved nozzle and filler spout partially broken away.

Fig. 3 is a vertical section through the filler spout showing the arrangement of the lower baffles and adjoining parts.

Fig. 4 is a partially cut-away perspective showing the arrangement of the upper baffles.

Fig. 5 is a plan view of an authorized connected nozzle and spout showing the retaining means.

Fig. 6 is a perspective of a part of the bottom of the filler spout showing the cut-away portion.

Fig. 7 is a vertical section through a modified form of receiving bottle top and filling nozzle.

Fig. 8 is a horizontal section on the line 8—8 of Fig. 7.

Fig. 9 is a detail of the nozzle with the pouring lip in operative position.

Fig. 10 is a vertical section through a still further modified form of connection showing a different form of receptacle top and the connection therewith.

Fig. 11 is a vertical section at right angles to Fig. 10 and substantially on the line 11—11 thereof.

Fig. 12 is a bottom plan view of the receptacle top and pouring spout shown in Fig. 10.

Fig. 13 is a vertical section through the pump nozzle shown in Figs. 10 and 11.

The invention is illustrated as used in a system of apparatus comprising one or more glass bottles 1, such as are commonly used for dispensing lubricating oil at retail. Each bottle is provided with a metal top 2 providing the usual pouring snout.

For the purpose of refilling the bottle, a pump 4 is connected with a suitable source of supply. The bottle top and the outlet pipe 5 of the pump are provided, respectively, with a filling spout and a nozzle, formed to cooperate with each other and embodying the present invention.

As best shown in Figure 2, the spout 3 is the shape of a frustum of a cone and is fastened permanently to the inside of the top 2 by a screw threaded collar 7 on the reduced inner end portion and has a series of apertures 8 in the faces of the outwardly projecting surface portions. 75

The nozzle 6 is likewise provided with cone shaped sides 9 apertured at 10 to correspond and cooperate with the apertures 8 in the spout 3. The portion 11 of the nozzle between the inwardly projected cone sides 10 and the tubular sleeve 12 is open to afford a channel directly to the oil source. On the periphery of the cylindrical portion 12 is a means for temporarily retaining the filling spout and receiver while being filled from the nozzle 6. It is here shown as a lug 13 85 notched to engage with an upwardly projecting pin 14 screwed into the filling spout 3. A partial turn is sufficient to bring the lug in contact and to align the series of holes 8 and 10 to allow filling of the receptacle or bottle 1. 90

The bottle top 2 is fastened to the receptacle 1 by bending over and crimping the edges 15 under the shoulder on the bottle as shown in Figure 3. In assembly, a cork or other cushion gasket 16 is placed between the top of the bottle 95 and the bottom of the snout 2 to insure a tight joint without injuring the bottle. The top 2 contains a check-valve 17, which is hinged at 17a so as to open when the bottle is inverted, but which prevents refilling through the snout. The top also contains a baffle 18, to prevent tampering with the valve 17, which as best shown in Figure 4, consists of two crossed plates practically hindering any and all attempts to open the valve 17 to effectively prevent filling of the bottle through 105 the top of the bottle cover 2.

Although the holes 8 are sufficient in number to permit the bottle to be filled quickly and easily through the nozzle 6, they are too small, individually, to permit oil to be poured in or intro- 110

duced conveniently by any ordinary means. To prevent refilling from an unauthorized source by means of a hose placed over the filling spout, a groove 19 is channeled in the lower surface of the spout, as shown in Fig. 6, so that oil passed through the hose would escape through this groove, to a considerable extent, instead of entering the holes 8.

In the modified form shown in Figures 7, 8 and 9, the receptacle top 2a, is similar in shape to that shown at 2 in Figure 1, and is similarly provided with a filling spout 3a which however is of a different shape, more difficult to fill and easier to construct. This form is of frustro-pyramidal shape the vertical planar sides of which are provided with a series of apertures 8a through which the fluid enters. Integral with the end of the conveying pipe 5a which is purposely inclined to allow drainage to the filling source, is the cooperating embracing flange nozzle 6a which has aligned apertures 10a to coact with the holes 8a and convey the oil or other fluid from the conveying pipe to the interior of the bottle or other measuring receptacle.

25 The nozzle end 6a has a surmounting boss 20 in which is a vertical slot 21 as shown in Figure 9, and the bottle top 2a has a boss 22 above the pyramidal filling spout and through which projects a horizontal pin 23, adapted to enter the slot 21 in the nozzle end.

The baffling devices 24 in the pouring snout are different from those shown in Figs. 2 and 3, but need not be described, as they constitute no part of the invention claimed herein.

35 If it is desired to use the nozzle 6a without filling the receptacle 1a, for example when it is desired to draw a small quantity of oil into an open receiver, to prevent spouting of the liquid, lip baffle 25 hinged at 26 to the boss on the end of the nozzle 6a may be turned down from the open position in Figure 7 to the closed position in Figure 9. This will then cause the liquid to flow directly down out of the open end 27 of the nozzle.

When the contents are poured from the bottle 45 the filling spout serves as an effective air inlet, but does not readily permit the escape of liquid through the small holes if the bottle is held with the spout on the upper side of the pouring snout.

A still further modified form of connection shown in Figs. 10 to 12, inclusive, comprises a metallic discharge snout 2b secured to a receptacle (not shown) which is filled through the filling spout 3b from the end of the oil discharge pipe 5b through the discharge nozzle 6b.

55 As best shown in Figs. 10 and 12, the filling spout 3b is substantially wedge shape having its larger base at the top, and is provided with a plurality of apertures 8b in the sloping side walls. It is to be understood, however, that any wedging shape would operate for the purpose disclosed. The spout communicates, through an opening 9b, with the body of the receptacle.

The nozzle 6b is provided with an integral U-shaped hollow head 10b which is adapted to receive the filling spout 3b. Near the top of each of the lateral members 10b of the nozzle is a row of apertures corresponding to and adapted for communication with the apertures 8b in the filling spout. A limit pin 14b limits the distance that the filling spout 3b may be inserted in the U-shaped portion, and by a proper coordination of the apertures 12b in the side of the discharge nozzle 10b, the limit pin 14b and the apertures 8b in the filling spout, communication will be 75 opened directly from the the interior of the noz-

zle head to the interior of the receptacle. It is also obvious that the apertures may be variously arranged similar to the tumblers in a tumbler lock so that but one combination will fit a designated series of nozzles. In other words, the number, size and location of the apertures may be varied so that but one combination will be operative.

80 A cover plate 16b fastened to the top of the U-shaped head 10b cooperates with the top of the filling spout 3b and a cam and lever 18b mounted on the head and extending over the cover plate may be rotated to press the cover plate against the top of the spout so that the filling spout is wedged securely between the side-members 10b of the nozzle and no leakage will occur. Upon being released, the cam will take the position shown in full lines in Fig. 13 and will allow the filling spout to be released from the filling nozzle.

85 To prevent dripping of oil from the pump when not in use, the holes 12b are located as near the top of the nozzle head 10b as possible, and the conduits 20b leading thereto are downwardly inclined so that when the pumping is stopped and the spout 3b removed from the nozzle, the oil in the conduits 20b will drain back to the pump and will not drip from the openings 12b. The areas of the apertures 8b and 9b may be regulated to insure adequate flow of oil through the aperture 9b to drain the filling spout as rapidly as oil is pumped therein through the apertures 8b, and as these apertures are located at the top of the side walls of the spout, there is no drip when the spout is removed from the pump.

90 In order to take care of possible oil drip caused by operation of the pump when no spout is in place, a catch basin 22b is formed under the nozzle head 6b and is provided with a return conduit 24b which may desirably lead to the receptacle to permit the oil to return thereto. This drip basin 22b will preferably extend up the inner side of the nozzle to seal the nozzle from dirt and to insure the catching of all the oil which does not actually pass into the receptacle to be filled.

95 The baffles 26b and the check-valve 28b, shown in Figs. 10 and 12, have the same functions as the corresponding parts in the other illustrated embodiments of the invention.

What we claim is:

1. In combination, a liquid discharge nozzle, an intake spout, the discharge nozzle cooperating with the intake spout, both parts being provided with a series of small apertures each pair of apertures being in simultaneous registration to allow simultaneous discharge into said intake spout from said cooperating discharge nozzle, said discharge nozzle having a clamping mechanism whereby said nozzle and intake spout are forced into close communication.

2. In combination, a frustro-pyramidal intake spout having a series of apertures through the sides thereof and a cooperating discharge nozzle, provided with a series of aligned apertures through the inner sides thereof to allow passage of fluid therebetween.

3. In combination, a wedge shape intake spout, an embracing, key discharge nozzle, the wedge shape intake spout being provided with an imperforate smaller base and end.

4. As an article of manufacture, a nozzle for dispensing machines comprising a cylindrical sleeve, a frustro-conical portion whose larger base is integral with the sleeve and whose smaller base is imperforate and extends into the sleeve, the

5 sides of the frustro-conical portion being apertured for the discharge of fluid therefrom.

5. In combination with fluid discharge means and fluid receiving means, a filling spout projecting from the fluid receiving means, the sides of the spout solely being perforated, a nozzle, the sides of said nozzle being apertured in cooperative relation with the perforations in the filling spout, and other means to divert liquid during filling of the fluid receiving means without the use of the pre-designed nozzle.

6. An article of manufacture of the class described, a key discharge nozzle for a dispensing source, comprising an upwardly inclined portion, a horizontal end portion, an inwardly inclined hollow frustro-pyramidal portion, whose larger base is integral with the end of the nozzle and whose smaller base is imperforate, the lateral sides only being apertured to permit flow of liquid therefrom.

7. As an article of manufacture, a nozzle for dispensing machines comprising a substantially cylindrical sleeve, a substantially wedge shape portion having a smaller base, a larger base and vertical lateral sides therebetween said larger base being integral with the sleeve, and said smaller base being depressed within the cylindrical sleeve, the vertical lateral sides of the wedge shape portion being apertured to discharge liquid therefrom.

8. In a dispensing system of the class described having an inflow conduit and a discharge nozzle to discharge liquids into the inflow conduit, said conduit and nozzle comprising hollow telescoping parts, said parts having transversely apertured sides, and means to force said sides into cooperating relation whereby liquids may pass into said inflow conduit through the apertures.

9. The combination with an inflow conduit for a non-refillable receptacle of a female discharge nozzle cooperating therewith, said inflow conduit having a male filling spout provided with a plurality of small apertures along a planar side thereof and having an imperforate end, said discharge nozzle having a plurality of similar small apertures to cooperate with said first mentioned apertures, means to force the two members into liquid tight contact and drip means to divert flow of liquid from entering said inflow conduit except when discharged by said discharge nozzle.

10. In combination, a discharge nozzle, an in-

take spout, said discharge nozzle having a U-shaped head thereon, the inner sides of the U being apertured and in liquid communication with the center of said nozzle, said intake spout being wedge-shaped and being apertured along the sides thereof, and a cam means to force said wedge-shaped intake spout into liquid tight communication with said discharge nozzle.

11. In combination, a discharge nozzle, an intake spout, said nozzle and spout having cooperating apertures therein, the discharge nozzle closely embracing the intake spout, both parts being provided with cooperating conduits extending to the apertures in the adjacent parts for liquid communication therebetween, the conduits in said nozzle being at a slight upward angle to the horizontal to allow surplus oil to return to the nozzle.

12. In combination, a wedge-shaped intake spout having an imperforate end and being provided with conduits along its planar sides, a U-shaped discharge nozzle having conduits along its planar sides, means to force said intake spout into fluid tight communication with said discharge nozzle, and means to prevent drip when said intake spout is removed.

13. In a dispensing apparatus of the class described, comprising a discharge nozzle and a male intake spout, said intake spout being provided with a combination locking arrangement of apertures in the sides thereof, and having an imperforate end in said spout, said discharge nozzle being similarly provided with a locking combination of apertures, means to force said apertures in fluid communication, and means to prevent the loss of oil after the intake spout has been removed.

14. In combination, two cooperating hollow fluid-conducting members constituting, respectively, a discharge nozzle and an intake spout, one of said members having relatively inclined outwardly directed surfaces and the other having corresponding inwardly directed surfaces against which the said outwardly directed surfaces may be wedged in substantially fluid-tight engagement, the members having, in said surfaces, a plurality of registering small perforations for conducting fluid from the hollow interior of one member to the hollow interior of the other.
